UNITED STATES PATENT OFFICE.

THOMAS WILLETT, OF BURSLEM, COUNTY OF STAFFORD, ENGLAND.

POTTERY-MACHINE.

SPECIFICATION forming part of Letters Patent No. 268,583, dated December 5, 1882.

Application filed July 5, 1882. (No model.) Patented in England March 8, 1881, No. 981; in France September 5, 1881, No. 144,717, and in Belgium September 6, 1881, No. 55,666.

To all whom it may concern:

Be it known that I, THOMAS WILLETT, a subject of the Queen of Great Britain and Ireland, residing at Burslem, in the county of Stafford, England, have invented a new and useful Improvement in Pottery-Machines, (for which I have obtained Letters Patent in Great Britain and Ireland, No. 981, dated March 8, 1881; in France, No. 144,717, dated September 5, 1881, and in Belgium, No. 55,666, dated September 6, 1881,) of which the following is a specification.

This invention relates to improvements in the manufacture of pottery and earthenware by machinery which is mainly automatic in its operations upon the clay or other plastic material supplied thereto, whereby articles of given patterns can be multiplied with great rapidity and mechanical uniformity. Machinery of this general character heretofore proposed, owing to complexity and other real or apparent defects, has been introduced into practical use to only a very limited extent, if at all. The old potters' lathes and hand-tools are still commonly used, so far as I am informed, throughout the United States, as well as in England and elsewhere.

My present invention consists in an improved automatic machine for potters' use, designed with reference to practical simplicity and efficiency; and more particularly, first, in a novel combination of parts for the actuation of one or more (preferably two) tools or profiles by means of continuously-rotating cams, whereby they are lowered and held with great steadiness; secondly, in a novel combination of parts, including means for rotating the cam-actuated tools or profiles, (instead of rotating the molds,) which in practice has been found to give a more perfect shape to the article being manufactured, and also provides for finishing the same in a comparatively quick manner; thirdly, in a novel combination of parts, including a pair of cams acting simultaneously, and a rotary mold-table having a concentric series of molds so arranged that diametrically-opposite molds form pairs beneath the respective tools or profiles, as hereinafter more fully set forth.

Figure 1 of the accompanying drawings is a front view of my said improved automatic ma-

chine. Fig. 2 is a top view thereof, and Fig. 3 is a face view of one of its cams; and Fig. 4 is a front view of a modified machine embodying the first part of the invention, with immaterial modifications. Fig. 5 is a top view thereof; and Fig. 6, a side view, partly in section, like letters of reference indicating corresponding parts in all the figures.

In each of the said machines a driving-pulley, A, is mounted on a vertical shaft, B, which carries a worm, C. This worm rotates a central worm-wheel, D, on a horizontal overhead shaft, E, which carries at its extremities a pair of cams, F, below which are a pair of tool or profile shafts, G, which said cams lower periodically, and beneath these is a horizontal mold-table, H, the whole supported by an upright metallic frame, I, provided with suitable bearings and guides, and by suitable steps and bearings attached to the floor and ceiling of the apartment within which the machine is located, as indicated on the drawings.

Suitable tools or profiles, t, and molds m, with means for attaching the former to the shafts G, and for adjusting them as to inclination and distance from the axes of the molds, are common to the preferred form and the modification, and may be of ordinary construction.

The shape of each cam is illustrated by Fig. 3, where an arrow indicates the direction of rotation; 1, an eccentric peripheral curve for slowly lowering the tool or profile shaft; 2, a curve concentric with the axis of rotation to hold the tool or profile to its work and for smoothing and finishing the same, and 3 an incline which permits the tool or profile shaft to quickly ascend so as to carry the tool or profile away from the work.

For convenience the respective sheets of the drawings will be hereinafter referred to for the two sets of figures which they bear in describing dissimilarities in the preferred machine and the modification.

The shafts G (shown on Sheet 1) are simply constructed with smooth upper ends to engage with the peripheries of the cams F. Those shown on sheet 2 are provided with anti-friction rollers a. For re-elevating the shafts G spiral springs J, between suitable collars, are shown on Sheet 1, and a weighted cord and

pulleys, J x, on Sheet 2. In addition to the said worm C, each vertical shaft B carries a pulley-drum, K, from which bands or belts L L extend to driven pulleys M M. On Sheet 1 5 these driven pulleys are shown as fast on sleeves s, embracing the tool or profile shafts G between the guide-projections of the frame I, and connected respectively to said shafts G by splines, so as to cause the latter to rotate therewith without obstructing their said up-and-down motion. It will thus be apparent 10 that the corresponding molds, m, Sheet 1, need simply be supported beneath the said rotary tools or profiles t and supplied with clay or other plastic material, as aforesaid, the machinery being in motion, when said tools or profiles will be lowered by the action of the cams F, and will, by rotating in contact with said plastic material, impart the required 15 shape to the same to form the inside and outside of the pottery or earthenware articles.

To provide for working both tools or profiles simultaneously, so as to equalize the strain on the respective sides of the machine, and at the same time to facilitate filling said non-rotary molds and removing the molded articles therefrom, said cams F are set on the shaft E, Sheet 1, so as to act simultaneously. The mold-table H, Sheet 1, is supported by a central vertical shaft, N, so as to be capable of rotation by hand, and said molds m are held in suitable vertical recesses so arranged in a circular series concentric with the axis of the table that molds diametrically opposite each other form successive pairs beneath the tool or profile shafts G, as shown on Sheet 1. In some cases I use with said arrangement of cam-actuated rotary tools or profiles a fixed mold-table, in which cases the tool or profile shafts are by 30 preference raised and lowered alternately by so mounting the cams F on the shaft E as to secure this alternate action.

I have shown on Sheet 2 a mold-table, H, fixed, and cams F mounted for alternate 45 action, in connection with non-rotary tool or profile shafts G and rotary molds, the latter carried in customary manner by ordinary jigger-spindles O O, upon which the driven pul-

leys M are secured, in lieu of upon the tool or profile shafts, the main shaft B being extended 50 downward to the floor in this modification and provided with the drum K at proper height. Said non-rotary shafts G, Sheet 2, are kept from turning, as shown, by the points of set-screws q within straight grooves r, formed 55 along said shafts. In some cases I cause such non-rotary tool or profile shafts to make partial rotations upon their axes as they descend by forming spiral grooves or otherwise suitably-shaped grooves therein for said set-screws 60 q to work in, so that by affixing the tools or profiles eccentrically they will be advanced or retracted or moved alternately outward and inward to form bowed, "bellied," or otherwise shaped articles. 65

Having thus described said invention and modification, I claim—

1. In a machine for making pottery or earthenware, the combination, substantially as herein described, of a vertical driving-shaft, B, 70 worm-gearing C D, horizontal shaft E, cams F, and perpendicular tool or profile shafts G with means for re-elevating the latter, for the purpose set forth.

2. The combination of the vertical driving-shaft B, the worm C, worm-wheel D, horizontal shaft E, cams F, and springs J, and the drum K, belts L, and pulleys M with the tool or profile shafts G, substantially as shown on Sheet 1 of the accompanying drawings, as herein specified. 75

3. The combination of the pair of cams F, set on their shaft E so as to act simultaneously, the pair of rotary tool or profile shafts G, with their springs J and tools or profiles t and 80 means for rotating said shafts, and the rotary mold-table H, with non-rotary molds m, arranged therein so as to form successive pairs of diametrically opposite molds beneath said tool or profile shafts, substantially as herein 85 described, and illustrated on Sheet 1 of the accompanying drawings. 90

THOMAS WILLETT.
